[57] CLAIM

The ornamental design for a vacuum cleaner for pets, as shown and described.

DESCRIPTION

FIG. 1 is a perspective view taken from the top, front and right side of a vacuum cleaner for pets showing my new design;

FIG. 2 is a bottom plan view thereof, with a portion shown broken away for convenience of illustration;

FIG. 3 is a front elevational view thereof; and

FIG. 4 is a rear elevational view thereof.
